UNITED STATES PATENT OFFICE.

ALVAH M. F. BILLINGSLEA, OF TOLEDO, OHIO, ASSIGNOR OF TWO-THIRDS TO
VALENTINE H. KETCHAM AND SAM T. FISK, OF SAME PLACE.

FOLDING BEDSTEAD.

SPECIFICATION forming part of Letters Patent No. 425,399, dated April 15, 1890.

Application filed June 17, 1889. Serial No. 314,620. (No model.)

To all whom it may concern:

Be it known that I, ALVAH M. F. BILLINGSLEA, a citizen of the United States, residing at Toledo, in the county of Lucas and State of Ohio, have invented certain new and useful Improvements in Folding Bedsteads; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to folding bedsteads of the class ordinarily combined to the wardrobe, book-case, or other articles of furniture.

The object of the invention is to provide a foldable bedstead of few parts and so arranged as to be convenient of manipulation and to entirely fold within the article of furniture to which it is pivotally secured.

In the drawings, Figure 1 is a perspective view of the rear and side of the book-case having a bedstead constructed in accordance with my invention pivotally secured thereto. Fig. 2 is a longitudinal vertical section through the same with the bed folded. Fig. 3 is a detail view of the section of the book-case, showing 25 yielding support for the bedstead when being folded. Fig. 4 is a sectional view of the same, showing the modified form of tension device. Fig. 5 is a front sectional view of the book-case showing anti-friction rollers secured thereto, and portions of the side rails and curved track into which the anti-friction rollers revolve. Fig. 6 is a detail view of a portion of the book-case and side roller, showing the rail and the rod attached thereto, which operates the leg 30 of the bedstead. Fig. 7 is a view of a section of one of the side rails, showing the curved track on which the anti-friction roller revolves, and also a projecting catch upon the end of the bed-frame for engagement with the spring.

A designates an article of furniture, which may be a book-case, a wardrobe, or any preferred article of analogous character formed with sides B B, projecting rearwardly from the back C. Upon each side B are formed curved 45 bearings D, onto which move anti-friction

rollers E, secured to the pivoted end of the foldable bed-frame F. Frame F comprises side bars G, foot-board H, and cross-bar H'. Upon each side B of the article of furniture 55 are pivoted anti-friction rollers I, which move in the trackway J upon each of the side bars G, the trackway being of the contour to allow the bed-frame when folded to rest with anti-friction rollers E near the floor, and when extended to allow said rollers to travel upon the curved portion D of the sides.

K designates a projecting hook, formed centrally of the length of bar H' and extending through the vertical slot K' in the backing C 65 of the book-case, said vertical slot serving also to guide the hook and prevent any possible lateral movement of the bed portion.

L designates a flexible counter-balance for the bed-frame when being lowered, and also 70 a means of assisting in raising the same when being folded, and consists of spiral springs M, connected by an intermediate rope M', secured to the sides of the book-case in front in the backing C and in the path of travel of the 75 hook K. Tension is given to the flexible counter-balance L by means of pulleys N, against the end side of which the rope M bears when put in tension, the pulleys N being adjustable by means of the threaded rod 80 N', by which said pulleys are raised or lowered, the lower ends of said rods normally resting on the lower part of the fixed portion, whereby they may be adjusted vertically.

The legs O of the bed-frame are pivoted to 85 the side bars at O', and are automatically folded when the frame is raised or thrown into proper position to support the frame when being lowered through the medium of rods P, secured to the legs at P' and extending along 90 the entire sides of the side bars G, being held in position by staples Q, and the front end of the rod being bent at right angles at P'' to pass through an elongated slot R in each side bar and project in the path of metal plates 95 S, secured upon the sides B B of the book-case.

With this construction the operation is as follows: The bed being folded, as shown in vertical section in Fig. 2, to lower the same 100 the operator pulls upon the frame F, causing the rollers E to move from their position near

the floor onto the curved bearing D, the anti-friction rollers I traveling in the trackway J and until the frame F has been moved about forty-five degrees, when the angle portion of 5 rod P strikes plate S, and as the bed-frame completes the angle of ninety degrees projects the legs in proper position to support the bed-frame.

To assist the operator in sustaining the 10 weight of the bed when being lowered, hook K engages with the flexible counter-balance L as soon as the frame has passed an angle of twenty degrees, and the tension of the counter-balance increases as the bed is lowered, thereby 15 almost entirely relieving the same of weight.

In folding the bed, it is only necessary for the operator to exercise a slight degree of force, as the counter-balance L aids in raising the same.

20 In Fig. 4 I have shown a modified form of producing tension upon the counter-balance L, which consists of a threaded rod T, passed through the frame of the book-case, and having a collar T', which bears against the portion of the spring M threaded upon the rod T. In this construction, to increase the tension of counter-balance L, it is only necessary to turn the rod T, thereby depressing collar T' and increasing the tension upon the 25 support.

30 It will be seen that the operative parts are simple of construction, efficient in operation, and not liable to get out of repair.

What I claim is—

35 1. In a folding bed, the combination, with a fixed portion and the folding portion pivotally connected thereto, of the vertical rods having threaded ends and secured within the fixed portion near each side of the same and 40 each carrying a collar, the spiral springs secured to said rods below the collars and the rope connecting said spiral springs, and a projection carried by the pivotal portion adapted to engage said rope, all arranged and adapted 45 to operate substantially as described.

2. In a folding bed, the combination, with a fixed article of furniture, of a flexible counter-balance extending transversely across the same and secured at the sides, said fixed portion 50 having a vertical slot formed in its rear side, and a foldable bed portion pivoted to the fixed portion and carrying a forwardly-

projecting hook extending through and guided by the vertical slot, said hook engaging with the flexible counter-balance, substantially as 55 shown and described.

3. In a folding bed, the combination, with a fixed portion having anti-friction rollers upon the inner sides thereof and curved tracks secured to said sides below the rollers, 60 of a foldable bed portion having semicircularly-curved bearing-tracks upon the outer sides of the same near its rear end, adapted to run on the anti-friction rollers secured to the inner sides of the fixed portion, and the anti-friction rollers carried at the rear ends of the foldable bed portion, adapted to engage the curved tracks secured upon the fixed portion, 65 substantially as shown and described.

4. In a folding bed, the combination, with 70 a fixed portion, of a flexible counter-balance extending transversely across the fixed portion and secured thereto at the sides and the vertically-adjustable bars connected with the flexible counter-balance to regulate the tension of the same, said counter-balance consisting of coiled-spring end portions and a central connecting cord or rope adapted to be engaged by a hook upon the foldable bed portion, substantially as shown and described. 75

5. In a folding bed, the combination, with a fixed portion having anti-friction rollers upon the inner sides thereof and curved tracks secured to said sides below the rollers, 80 of a foldable bed portion having semicircularly-curved bearing-tracks upon the outer sides of the same near its rear end, adapted to run on the anti-friction rollers secured to the inner sides of the fixed portion, the anti-friction rollers carried at the rear ends of the 85 foldable bed portion, adapted to run upon the curved tracks secured upon the fixed portion, and a flexible counter-balance secured within the fixed portion and adapted to be engaged by the folding portion, whereby the movements of said portion are steadied, as set forth. 90

In testimony that I claim the foregoing as my own I hereby affix my signature in presence of two witnesses.

ALVAH M. F. BILLINGSLEA.
